UNITED STATES PATENT OFFICE.

CHARLES H. BAYLEY, OF BOSTON, MASSACHUSETTS, ASSIGNOR TO
UNITED SHOE MACHINERY COMPANY, OF PATERSON, NEW JER-
SEY, A CORPORATION OF NEW JERSEY.

SKIVING-MACHINE.

No. 823,578.

Specification of Letters Patent.

Patented June 19, 1906.

Application filed June 11, 1902. Serial No. 111,168.

To all whom it may concern:

Be it known that I, CHARLES H. BAYLEY, a citizen of the United States, residing at Boston, in the county of Suffolk and State of Massachusetts, have invented certain Improvements in Skiving-Machines, of which the following description, in connection with the accompanying drawings, is a specification, like reference characters on the drawings

representing like parts in the several figures.

This invention relates to a machine for skiving leather, and is shown in the drawings and is herein described as embodied in a machine in which a rotary disk cutter is employed set in proper relation to a work-support so that as a piece of leather is fed toward the rotary cutter a strip will be so cut from the edge of the leather as to leave said edge skived or beveled.

Many portions of the machine to which the present invention is shown as applied are substantially the same as corresponding parts of the machine shown and described in United States Letters Patent No. 636,942, granted to me November 14, 1899.

One feature of the invention consists in an improvement in the knife-actuating means whereby the operative connections of the knife to the driving-shaft are adjusted simultaneously with the adjustment of the knife toward and from the work-feeding mechanism, such adjustment of the knife being frequently necessary for different work.

It has been customary to actuate the skiving-knife from the driving-shaft by intermeshing beveled gears, as illustrated in the machine shown in the Letters Patent above mentioned. In adjusting the knife toward and from the feeding mechanism for the purpose of varying the width of the skiving it has been necessary in machines so arranged, first, to loosen the gear carried by the driving-shaft, then adjust the knife to the new position, and thereafter to adjust the gear on the driving-shaft to a position in which it would mesh with the gear carried by the knife-shaft. This consumed considerable time and required some skill on the part of the operator. To overcome this objection, I have connected the knife to the driving-shaft by means which is simultaneously adjusted by the same operation which adjusts the knife

to the various positions the knife is required to occupy without any manipulation on the part of the operator.

The invention further consists in providing an additional adjustable support for the knife-shaft, by means of which the usual tendency of the shaft to wear its bearings unevenly due to the lateral pulley strain is neutralized.

It has been found that where the knife-shaft for rotary skiving-machines has been actuated by a belt connection with the driving-shaft the lateral strain of the belt on the shaft causes the shaft to tilt toward one side, and consequently to wear its bearings unevenly, so that it is necessary to renew such bearings frequently in order to keep the knife running steadily. I have therefore provided a support to resist this lateral strain on the knife-shaft and have so mounted this support that it may be adjusted to position the shaft accurately and to compensate for wear.

These improvements are embodied in the machine shown in the accompanying drawings, in which—

Figure 1 is a side elevation of the complete machine. Fig. 2 is a side elevation of the machine with the frame removed which carries the knife and the pair of idle pulleys herein-after to be referred to. Fig. 3 is a side elevation of said knife-carrying frame. Fig. 4 is an elevation of the knife-carrying frame from the side opposite to that shown in Fig. 3. Fig. 5 is a rear end elevation of the machine. Fig. 6 is a side elevation of the machine with the feeding-disk and grinder removed and with certain parts broken away in order to show the means for tilting the knife. Fig. 7 is a sectional view on line 7-7 of Figs. 1 and 6. Fig. 8 is a top plan view of the left-hand portion of Fig. 6 and shows my improved adjustable support for the upper end of the knife-shaft. Fig. 9 is a section on line 9-9 of Fig. 1.

A indicates the machine-frame, adapted to rest upon a table or other base and of suitable shape to support and guide the movable parts of the machine.

2 indicates the driving-shaft, actuated from a suitable source of power. This driving-shaft is provided at 3 with a worm, which engages a worm-gear 4 upon the shaft 5, which,

through beveled gears 6 6, actuates the shaft 7, carrying the work-support or lower feeding member 8.

10 indicates a worm on the left-hand portion of the driving-shaft. The worm 10 actuates a worm-gear 11, carried by the shaft 12.

13 indicates a feeding-disk mounted on the lower end of shaft 12 and adapted to coöperate with the work-support 8 in feeding the work.

14 indicates a spring on the shaft 12. The spring is arranged to bear at its upper end against the shaft-bearing 1^a, and at its lower end against a movable collar 12^a on the shaft 12. This spring thereby operates to press the feed-disk yielding upon the work carried by the work-support 8.

16 indicates a suitable edge gage to aid the operator in properly presenting the work.

20 B indicates a knife-frame, which is adjustably secured to the machine-frame A by a dovetailed connection 37 and a clamping-screw 31. (See Fig. 7.) A knife-bracket B' is attached to the frame B by the screw-bolt 33 and clamping-screw 34. The clamping-screw 34 passes through a slot b² in the knife-bracket, which permits of the bracket being tilted on the screw-bolt 33 as a pivot and then secured in adjusted position by the 30 clamping-screw. To facilitate the tilting of the knife-bracket, its rear end is provided with worm-teeth b³, adapted to be engaged by a thread on an adjusting-screw X. The knife-bracket supports a disk knife 22. (See Fig. 6.)

35 The knife-shaft 20 rotates in a fixed sleeve 200. The sleeve is provided with an enlarged portion 201, recessed or slotted to receive a collar 202, fixed on the shaft. (See Figs. 6 and 7.) The enlarged portion is also adapted to be engaged by an adjusting-screw g, (see Figs. 1 and 7,) movable in a bearing in the frame B'.

40 The machine as thus far described is the same as that disclosed in the Letters Patent above mentioned.

45 The frame B is provided with an extension C, shown as integral therewith. On this extension is mounted a pair of idle pulleys 26 26. 50 These pulleys are arranged upon opposite sides of a vertical plane passing through the axis of rotation of a pulley 25, fast on the driving-shaft and preferably somewhat below said pulley 25, as shown in Fig. 5. The 55 knife-shaft is provided with a pulley 23, adapted to receive a belt 24, extending from the pulley 25 on the driving-shaft 2. The belt 24 passes from said pulley 25 under one of said idle-pulleys, then around the pulley 23 60 of the knife-shaft, and thence around the other idle pulley and back to the driving-pulley. The driving-pulley is substantially cylindrical and has its axis parallel with the

line in which the frame B is adjustable, so that the bight of belt formed by the three 65 pulleys 26 25 26 will be maintained by them, so as to be always of the same form, length, and tension in all positions of the frame B within its limit of adjustment. In adjusting the frame B to vary the position of the knife 70 with relation to the feeding mechanism the idle pulleys are moved with said frame, and they move the belt along the driving-pulley from side to side thereof without affecting the tension of the belt. In adjusting the 75 knife it is therefore only necessary to loosen the clamping-screw 31 and move the knife-frame B along the main frame A to its desired position and then to tighten the clamping-screw. The idle pulleys and the belt 80 will in this movement have been simultaneously adjusted with relation to the driving-shaft and driving-pulley.

To regulate the tension of the belt 24, one of the idle pulleys 26 is mounted upon the 85 plate 29, which is adjustable on an extension b⁶ of the frame B. The plate 29 is clamped in adjusted position by a suitable clamping device 29^a.

90 It has been found in practice that the strain of the belt 24 upon the knife-shaft 20 causes said shaft to tend to tilt in the direction of such strain and to wear its bearings unevenly. It is very essential in a skiving-machine employing a rotary disk knife that 95 the knife be so mounted as to run steadily. I have therefore provided this machine with an additional bearing 27. (Shown in Figs. 1, 6, and 8.) This bearing is arranged above the pulley 23. The bearing is provided with a 100 shank 28, adjustably held in a clamp b⁵ of the knife-carrying frame. This bearing or support 27 may be adjusted with relation to the knife-shaft 20 to support the shaft against the strain of the belt and insure that said 105 shaft shall run steadily. The bearing or support may also be adjusted toward the shaft as either of them becomes worn away.

110 The operation of the machine will now be briefly stated.

115 The parts being adjusted to the positions shown in Fig. 1, the machine is started by operating a suitable clutch. (Not shown.) The workman presents a piece of leather which is to be skived, with its edge against the edge guide 60. The rotary work-support and the feeding-disk grasp the leather and rapidly feed it along against the skiving-knife, which so trims it as to form a beveled edge thereon. When it is desired to adjust 120 the knife for a different width of skiving, it is necessary merely to loosen the clamping-screw 31. The frame B, which carries the knife and the idle-pulleys, may be then moved to position the knife properly and the 125 clamping-screw again tightened, whereupon

the machine is ready for operation. This movement of the idle pulleys with the knife-frame simultaneously shifts the driving-belt 24 along the driving-pulley 25 without either slackening or tightening the belt. The operative connection between the knife-shaft and the driving-shaft is thus maintained in whatever position the knife is caused to occupy.

The machine embodies a knife-sharpening device 50, driven by a belt 51, to which tension is applied by a belt-tightening device 52, as is usual in machines of this type. Such grinding device and its operative connections are shown and described in United States Letters Patent No. 609,868, granted to me August 30, 1898, and need not be herein further referred to.

In the foregoing description some parts of the machine have been omitted or only briefly mentioned, since they have no bearing on the present invention and have been already described in detail in the patents referred to. So much of the machine, however, as embodies the present improvements has been fully described and illustrated in a practical form.

It is not intended to limit the invention solely to the form shown, since modifications may be made without departing from the principle of the invention.

Having thus described my invention, what I claim is—

1. A skiving-machine comprising a machine-frame, a knife-frame, adjustable with relation to the machine-frame, a driving-shaft carried by said machine-frame and provided with a pulley, a movable knife carried by said knife-frame, idle pulleys also carried by said knife-frame, and a belt connecting said driving-pulley and said movable knife to actuate the latter, said belt being adapted to be passed around said idle pulleys, whereby the tension of said belt is maintained substantially uniform in the varying relative adjustments of the said frames.

2. A skiving-machine comprising a machine-frame, a driving-shaft mounted thereon, a pulley on said shaft, a work-feeding mechanism also mounted on said frame, a knife-frame, a movable knife supported thereon, means whereby said two frames may be adjusted to vary the relative positions of the knife and work-feeding mechanism, an extension carried by the knife-frame, a pair of idle pulleys carried by said extension, and a belt connecting said driving-pulley and said movable knife to operate the latter, said belt being passed around said idle pulleys, whereby the tension of the belt is maintained substantially uniform in the various adjustments of the two frames.

3. A skiving-machine, comprising a machine-frame, a driving-shaft mounted there-

on, a pulley on said shaft, a work-feeding mechanism also mounted on said frame, a knife-frame, a movable knife supported thereon, means whereby said two frames may be adjusted to vary the relative position of the knife and work-feeding mechanism, an extension carried by the knife-frame, a pair of idle pulleys carried by said extension and a belt connecting said driving-pulley and said movable knife to operate the latter, said belt being passed around said idle pulleys, whereby the tension of the belt is maintained substantially uniform in the varying adjustments of the knife toward and from the work-feeding mechanism, in combination with means permitting adjustment of one of said idle pulleys to regulate the tension of the belt.

4. A skiving-machine comprising a suitable frame, a driving-shaft mounted thereon, a rotatable skiving-knife, a support for the knife connected to the frame for adjustment in the direction of the length of the driving-shaft, means for securing the knife-support in adjusted position, intermediate mechanism connecting said driving-shaft and knife to actuate the latter, and means movable with the knife-support for effecting adjustment of said connecting mechanism simultaneously with the adjustment of the knife and knife-support whereby to compensate for variations in the position of the knife with relation to the driving-shaft.

5. A skiving-machine comprising a driving-shaft, a pulley mounted in fixed relation thereon, a cutter, mechanism connecting said cutter and the driving-pulley, and means whereby said cutter may be adjusted longitudinally of the driving-shaft toward and from the pulley while maintaining the operative connection between the cutter and pulley.

6. A skiving-machine comprising a driving-shaft, work-feeding mechanism, a cutter, connecting mechanism between said cutter and the driving-shaft, and a support for the cutter movable in the direction of the length of the driving-shaft, said machine having provision for adjusting said support and cutter longitudinally of the driving-shaft toward and from the work-feeding mechanism without disturbing the operative relation of the connecting mechanism with the shaft and cutter.

7. In a skiving-machine, a knife-shaft mounted in suitable bearings, a knife carried on the end of said shaft, a pulley also carried by said shaft near the opposite end, a driving-shaft, a belt connecting said driving-shaft and said pulley, and a support for the end of the knife-shaft adjacent to the pulley to resist lateral strain due to the belt and to prevent uneven wear of the shaft-bearings.

8. In a skiving-machine, a shaft mounted in suitable bearings, a rotary skiving-knife mounted on said shaft, a pulley carried by said shaft near one end, and an adjustable 5 half-bearing for said shaft at the end adjacent to the pulley to support the shaft against lateral strain.

In testimony whereof I have signed my name to this specification in the presence of two subscribing witnesses.

CHARLES H. BAYLEY.
